UNITED STATES PATENT OFFICE

RUSSELL K. NASH, OF BROOKLINE, MASSACHUSETTS, ASSIGNOR TO BOSTON BLACKING & CHEMICAL CO., OF BOSTON, MASSACHUSETTS, A CORPORATION OF MASSACHUSETTS

DISPENSING APPARATUS

Application filed April 28, 1931. Serial No. 533,479.

This invention relates to dispensing devices and is illustrated herein as embodied in apparatus developed for applying a coating of a heavy viscous cement to a strip of fabric.

Letters Patent of the United States No. 1,771,388, granted July 22, 1930 on an application filed in the name of the present applicant, and applicant's copending application Serial No. 468,017, filed July 15, 1930, disclose apparatus which is in successful use in applying an adhesive having a very high viscosity and commonly spoken of as "dough" to the surface of a strip of previously coated duck used in the manufacture of gem and economy insoles by the cold process. It is an object of the present invention further to improve dispensing apparatus of this character and to provide such an apparatus well adapted to receive and to facilitate the handling of large commercial containers of adhesive, larger than can conveniently be used in connection with the apparatus disclosed in the patent and the application above referred to. Thus the illustrated apparatus is arranged to receive a large can or drum of adhesive, which is supported in such a manner that it can be swung into inverted position so that the adhesive can pass through the open end of the can or drum and through the nozzle of the apparatus directly to the surface of the sheet material on which it is to be spread.

To this end, and in accordance with features of the invention, the illustrated apparatus is provided with a stationary frame to which is trunnioned a swingable frame adapted to receive an open-ended drum or other large container of adhesive and with a nozzle, one end of which conforms to and receives the open end of the container and the other end of which receives the strip or strips of material to which the coating is to be applied. This nozzle may advantageously be provided with mechanism for controlling the thickness of the coating in the manner disclosed in the Nash Patent No. 1,771,388. In the preferred machine, in accordance with another feature of the invention, a simple mechanism, illustrated as toggles, is

utilized to clamp the nozzle to the container and the nozzle and container to the swingable frame. After the parts have been secured together in this fashion, with the open end of the container up and with the nozzle secured thereto, a strip or strips of fabric are passed across the nozzle. The swingable frame, together with the can and nozzle, are then inverted and latched in position with the open end of the container downward so that the adhesive will pass by gravity from the can to the nozzle and will be applied by the nozzle to the strip or strips of material.

In accordance with still another feature of the invention a latch is carried by the stationary frame of the illustrated apparatus and cooperates with the swingable frame to maintain the swingable frame either in container-receiving position or in inverted operative position as may be desired. In accordance with still another feature, the strip engaging portion of the nozzle is provided with a bar or plate hinged at one side of the nozzle and normally maintained in operative position by a latch at the other side of the nozzle, and thus supporting the strip material as it is pulled past the nozzle but permitting the plate to be easily swung away from the nozzle when the container is positioned nozzle upwardly. This construction permits a new strip or strips to be readily supplied, after which the plate is returned to and latched in operative position so that, upon inversion of the swingable frame, the container and the nozzle, the strip material may be pulled past the nozzle and thereby receive a coating of adhesive.

In order to economize on strip material and at the same time to reduce the number of dispensing devices which are necessary, the present apparatus is made to receive two strips of material which may be of different widths, selected with a view to the widths of the insoles in the manufacture of which each individual dispensing device is to be used. As illustrated and in accordance with a feature of the invention, these two strips are pulled through a single slot in the nozzle, a removable closure illustrated as a block being used to separate the slot into two parts,

one for each strip of material. Thus by using one or another of a series of closures of different lengths the dispensing apparatus may be adapted to receive strips of fabric of different widths. Normally a closure will be used such that the apparatus will handle two strips one of which is somewhat narrower than the other, the narrower strip being used in the manufacture of smaller in-
10 soles and the wider being used in the manufacture of larger insoles.

With the above and other objects and features in view the invention will now be described with reference to the accompanying
15 drawings and pointed out in the claims.

In the drawings,

Fig. 1 is a perspective view of coating apparatus embodying the present invention and showing the parts in operative position;

20 Fig. 2 is a perspective view, looking down upon the apparatus, with most of the normally stationary frame omitted, showing the container positioned open end upward, with the nozzle in place, and with the hinged strip-
25 supporting plate swung upwardly so that strips of material can conveniently be positioned in operative relation to the nozzle;

Fig. 3 is an elevational view of the apparatus with the container positioned open end
30 upward;

Fig. 4 is an elevational view taken from a viewpoint at right angles to that from which Fig. 3 was taken, showing the apparatus on a smaller scale than Fig. 3, and showing
35 also a roll of strip material suitably supported and passing across the nozzle, ready for the inversion of the swingable frame, the container and the nozzle into operative position;

40 Fig. 5 is an elevational view of the strip receiving portion of the nozzle in operative position;

Fig. 6 is a transverse section, substantially on the line VI—VI of Fig. 5, but on an enlarged scale, of a portion of the nozzle taken through the block which separates the slot of the nozzle into two parts to receive two strips of different widths; and

Fig. 7 shows a tool which may be used to
50 punch a hole in the bottom of the container, after the swinging frame, the container and the nozzle have been inverted, to admit air to the container so that the adhesive will not be retained in the inverted container by atmospheric pressure.

The principal parts of the illustrated apparatus comprise a stationary frame 10 the upper end of which is open and on which is mounted a swingable frame 12 arranged to
60 carry a large can, drum or other suitable container 16 for adhesive and a nozzle 18 secured to the open end of the drum and to the swinging frame past which strips 20 of cotton duck are pulled so that a coating of
65 adhesive 22, contained originally in the drum

16 and passing from the drum 16 through the nozzle 18, is applied.

The frame 10 comprises a base portion 24 having a pair of upstanding arms 26 to which is trunnioned, as shown at 28, the approximately U-shaped swingable frame 12. In order to prevent tilting of the drum 16 relatively to the swinging frame when the drum is positioned open end upward, as illustrated in Figs. 3 and 4, but before it has been secured in place, a transverse member 30 (Fig. 1) is secured to the bar of the U-shaped swinging frame, the two last-mentioned parts forming a seat for the drum 16.

One end of the nozzle 18, which may be a casting of, for example, aluminum, is made circular and of a size to fit the drums 16, being provided with a tubular rubber gasket 32, indicated in dotted lines in Fig. 3, which, when the nozzle 18 is clamped to the drum 16, as will presently be explained, serves to form an air-tight seal between the two. The nozzle 18 is also provided with two pairs of lugs 34 placed to receive between them and to slide on the normally vertically extending arms of the swingable frame 12, thus restraining the nozzle from transverse movement relatively to the swinging frame. Means, illustrated as a pair of adjustable toggles 36, is provided for securing the nozzle 18 to the drum 16 and the nozzle 18 and drum 16 to the swingable frame 12 after the parts have been assembled and while the frame 12 is positioned open end up. Each toggle 36 comprises a pair of links 38 (best shown in Fig. 2) pivoted at one end to the nozzle 18 and connected at the other end to a pivot member 40 into which is threaded a screw 42, the head 44 of which

is elongated and arranged to cooperate with a hook-shaped portion 46 provided at the end of each of the arms of the swingable frame 12. When a drum 16 has been placed in the swinging frame 12, open end upward, and the nozzle 18 has been placed upon it, the toggles are swung into upstanding position with their heads 44 beneath the hook members of the swingable frame 12, and the pins of the toggles are forced respectively toward the upstanding portions of the frame 12 somewhat past dead center, the upwardly extending arms of the frame 12 springing slightly from the container as the toggle passes dead center. The nozzle 18 and the drum are thus clamped firmly together and to the swingable frame 12, with the parts in the position shown in Fig. 3.

To make it easy to apply a new strip or strips of fabric to the apparatus, a plate or bar 50 is hinged at one end, as shown at 52 (Figs. 2 and 5), to one side of the nozzle. Preferably the hinge is adjustably secured to the nozzle 18 as by screw-and-slot connections indicated at 54. To facilitate the adjustment the hinge 52 is provided with an

adjustable set screw 56 threaded into a lug 58 projecting from the hinge 52 and bearing against a portion of the exterior surface of the nozzle, as shown in Fig. 5. To the other side of the nozzle 18 a latch 60 is pivoted at 62 and is normally held by a compression spring 64 (Fig. 5) in latching engagement with a shoulder 66 formed on or secured to the nozzle 18, thereby maintaining the plate 50 in the position shown in Figs. 1 and 5 in which it serves to support the strip material 20 as the latter is drawn past the nozzle. When the container 16 is positioned open end upward, as shown in Figs. 3 and 4, the latch 60 may be released by pulling upwardly upon a projecting portion or handle 68 thereof, thus compressing the spring 64 and releasing the latch from the shoulder 66 so that by continued upward swinging movement the plate 50 may be swung into the position shown in Fig. 2, in which position it is supported by a finger 70 projecting from the hinge 52 and shown particularly in Figs. 3 and 5. With the parts in this position the strip material, a roll 72 of which may be supported on standards 74 located either on the floor, as indicated in Fig. 4, or on a bench, with the apparatus, is guided to the apparatus by a suitable guide or guides 76, each, as illustrated, comprising a pair of parallel rods or rolls placed a short distance apart and between which the strip material passes. From the guides 76 the strip is passed through the space between the bar of the swingable frame 12 and the adjacent portion of the stationary frame 10 and then upwardly above the nozzle 18 and is rested upon the outlet of the nozzle 18 after which the bar 50 is swung downwardly and latched in the position shown in Figs. 3 and 4. The frame 12 is then swung through 180° about its trunnions 28 into the position shown in Fig. 1 whereupon the operator may seize the end of the strip 20 and pull it through the apparatus which will apply the coating material to the upper side of the strip.

Preferably and as illustrated the apparatus is provided with mechanism, of the character disclosed in the Nash Patent No. 1,771,388 50 previously referred to, to control the application of the adhesive material to the strip. The illustrated apparatus, moreover, duplicates this mechanism and provides an additional means by which two strips of varying widths may conveniently be handled by the same apparatus. Thus the nozzle is provided with a pair of adjustable stripper plates 80 (Figs. 1, 3, 5 and 6) and with a corresponding pair of deflectors 82 adjustable to control the thickness of the coating applied. The opening for the strip of material pulled past the nozzle is in the form of a narrow slot the lower wall of which is formed by the plate 50, and the upper wall of which 60 is formed at the rear (as viewed in Fig. 1) by the cast metal of the nozzle 18 and at the front by the stripper plates 80, as indicated in Figs. 2 and 6. The outlet of the nozzle is divided into two portions by a closure shown as a block 84 secured by a screw 86 to a bridge formed in the nozzle. The block 84 projects upwardly from the casting of the nozzle so as substantially to contact with the plate 50 thus also dividing the slot into two parts for the reception of separate strips of material 20, forming guides for the adjacent edges of the two strips, and protecting the edge portions of the upper surfaces of the strips from the adhesive material. By utilizing the appropriate one of a series of blocks 84 the apparatus can be adapted to handle strips of any two of the widths which it may be desired to use.

To maintain the swingable frame 12 in can-receiving position or in operative position as may be desired, a latch 90 provided with a plunger 92 is pivoted at 94 to the stationary frame 10. The latch 90 is normally held by a spring 96 with the plunger 92 in one or the other of a pair of holes 98 and 100 drilled in the swingable frame 12, one or the other of these holes being in alignment with the plunger 92 according as the swingable frame is in one position or the other. To facilitate the operation of the latch 90, the swingable frame 12 is provided with a pair of inclined cam surfaces 102 and 104 (best shown in Fig. 2) adjacent to the holes 98, 100 which serve to cam the plunger 92 outwardly against the action of the spring 96 as the plunger reaches the hole, thereby relieving the operator of the necessity of maintaining pressure on the handle of the latch 90 as the container and swingable frame 12 are swung from one position to another.

A pair of leather-faced bumpers 101, 103, are formed on or secured to the swingable frame 12, in such position that one or the other will contact with the stationary frame 10 as the frame 12 is swung from one position to the other.

In order to permit air to enter the can 16 as the adhesive is used, a small hole may be punched in the bottom of the can with the aid, for example, of a tool such as that shown in Fig. 7 and comprising a heavy, for example cast iron, handle 106 adapted to be held in the hand of an operator, an end of which is provided with a spur 108. The weight of the tool is such that it can be grasped in the hand and slammed downwardly against the upturned bottom of the can, which at the time should be in the operative position shown in Fig. 1, thereby causing the spur 108 to go through the bottom of the can and forming a hole to let in air. If at any time it is desired to remove the can from the apparatus before its contents have been completely utilized the hole thus formed may be stopped up by cov-

ering it with a small piece of the strip material to which the adhesive has been applied.

Having thus described my invention what I claim as new and desire to secure by Letters 5 Patent of the United States is:

1. A coating apparatus comprising a normally stationary frame, a movable frame carried thereby and arranged to receive an open-ended container of coating material and a 10 closure nozzle separate from the movable frame for the container having a delivery opening, said nozzle being adapted to be applied to the open end of the container after the container has been received by the 15 movable frame, and means acting upon one of the parts received by the movable frame for pressing said parts into tight relation.
2. A coating apparatus comprising a normally stationary frame, a movable frame 20 carried thereby and arranged for the ready reception of an open-ended container of coating material and a closure nozzle having a delivery opening, said nozzle being adapted to be applied to the open end of the 25 container, means acting upon one of the parts received in said movable frame constructed and arranged to press said parts together and to hold them in the frame, and means for maintaining a strip of material to 30 be coated in operative relation to the delivery opening with the length of the opening extending transversely of the strip.
3. A coating apparatus comprising a normally stationary frame, an auxiliary U- 35 shaped frame swingably mounted in said stationary frame and arranged, when positioned with its open end upwardly, to receive an open-ended container of coating material, a closure nozzle for the open end of the 40 container, means on the closed end of said auxiliary frame for preventing displacement of the closed end of the container, and clamping means at the open end of the 45 U-shaped frame for holding the nozzle, container and frame in an assembled relation.
4. A coating apparatus comprising a normally stationary frame, a movable frame carried thereby and arranged to receive an open-ended container of coating material, a nozzle 50 received by the open end of the container, means for securing the nozzle and the container against movement relatively to each other and to the movable frame, and means 55 carried by the nozzle for controlling the application of the coating material to strip material drawn past the nozzle when the nozzle and the container are moved into an inverted position.
5. A coating apparatus comprising a normally stationary frame, a swingable frame 60 carried thereby and arranged to receive an open-ended container of coating material, a nozzle separate from the swinging frame and constructed and arranged to be received by the open end of the container.

means for clamping the nozzle to the open end of the container and for clamping the nozzle and the container against movement relatively to the swinging frame, and means carried by the nozzle to control, when the container and the nozzle are swung into inverted position, the application of the coating material to strip material drawn past the nozzle.

6. A coating apparatus comprising a normally stationary frame, a swingable frame carried thereby, a nozzle separate from the swingable frame and formed to receive the open end of a container of coating material carried by the swingable frame and arranged, when the container and nozzle are placed in inverted position by inverting the swingable frame, to conduct coating material to strip material drawn past the nozzle, means for clamping the nozzle to the open end of the container, means carried by the nozzle for supporting and guiding the strip material as it is drawn past the nozzle, and a latch arranged to secure the swingable frame against inadvertent movement when the container and nozzle are in inverted position.

7. A coating apparatus comprising a normally stationary frame, a swingable frame carried thereby, means for clamping a can of coating material and a nozzle fitting an open end of said can to the swingable frame, means arranged at the nozzle and effective, when the swingable frame, the can and the nozzle are in inverted position, to support strip material drawn past the nozzle, means for controlling the application of the coating material to the strip material drawn past the nozzle, and means for holding the swingable frame against inadvertent movement when the can and nozzle are in inverted position.

8. A coating apparatus comprising a normally stationary frame having its upper end open, a swingable frame trunnioned thereto, means for clamping a commercial container to the swingable frame including a nozzle constructed to be received by the open end of the container after the container has been received by the swingable frame, said nozzle having means arranged, when the container and nozzle are swung into inverted position, to control the application of coating material to a strip or strips of material drawn past the nozzle, and a latch arranged to secure the swingable frame against inadvertent movement when the container and nozzle are in inverted position.

9. A coating apparatus comprising a normally stationary frame, a swingable frame carried thereby having an open end and constructed and arranged to receive a container of coating material having an open end when said swingable frame is positioned open end upwardly, a nozzle one end of which is formed to be received by the open end of the

5 container, means carried by the nozzle for positioning the nozzle relatively to the swingable frame, means for securing the nozzle and the container tightly to each other and to the swingable frame, said nozzle being provided with means operative when the container and nozzle are in inverted position to control the passage of coating material from the nozzle to sheet material drawn past the nozzle, and means for maintaining the swingable frame with the container and nozzle in inverted position.

10. A coating apparatus comprising a normally stationary frame, a swingable frame 15 trunnioned thereto and constructed and arranged to receive an open-ended can of coating material, a nozzle one end of which is formed to be received by the open end of the can in tight relation thereto, interengaging members carried by the nozzle and the swingable frame respectively for positioning the nozzle relatively to the swingable frame, and means for clamping the nozzle to the swingable frame and the can and the nozzle to each 25 other, said nozzle being provided with means operative when the container is in inverted position to control the passage of coating material from the nozzle to a strip or strips of material drawn past the nozzle, and a latch carried by the normally stationary frame and arranged to maintain the swingable frame with the can and nozzle in coating-applying position.

11. A coating apparatus comprising a normally stationary frame, a swingable frame trunnioned thereto and constructed and arranged to receive a commercial container having an open end, a nozzle one end of which is formed and arranged to be received by the 40 open end of the container in tight relation thereto, guide lugs carried by the nozzle for positioning the nozzle relatively to the swingable frame, toggle mechanism for clamping the nozzle and the container to the 45 swingable frame and to each other, said nozzle being provided with means operative when the container and nozzle are in inverted position to control the passage of coating material from the nozzle to a strip or strips of 50 material drawn past the nozzle, and a latch arranged to maintain the swingable frame in container-receiving and in inverted position.

12. A coating apparatus having a nozzle 55 provided with an elongated opening through which a strip of material to be coated may be drawn and a removable closure for a portion of said opening whereby, by the use of closures of different dimensions, the nozzle 60 is adapted to apply coating material to strips of different widths.

13. A coating apparatus comprising a nozzle having an elongated opening through which strip material to be coated may be 65 drawn, and a removable closure for an inter-

mediate portion of said opening thereby dividing said opening into two portions through which separate strips of material may be drawn independently, whereby, by the use of closures of different dimensions, the apparatus is adapted to apply coating to strips of different widths. 70

14. A coating apparatus comprising a container, a closure nozzle for said container provided with an elongated delivery opening past which strip material to be coated may be drawn, a supporting member coacting with said nozzle to form a guideway for strips of material held in coating relation to the nozzle, and a removable closure for an intermediate portion of said guideway dividing the opening into two portions and the guideway into two sections through which separate strips of material may be drawn independently, whereby, by the use of closures of different dimensions, the apparatus is adapted to apply coating material to strips of different widths. 75 80

15. A coating apparatus comprising an open-ended container for coating material, a closure nozzle for said container provided with an elongated delivery opening, a bridge subdividing said opening into two parts, a removable closure secured to said bridge determining the widths of the parts of the opening, and means for supporting strips of material of different widths in coacting relation with said delivery openings whereby, by the use of closures of different dimensions, the apparatus is adapted to apply coating to a variety of widths of strip material. 90 95

16. A coating apparatus comprising a nozzle, means for securing the nozzle member to a commercial container of coating material, means for maintaining said container in inverted position whereby the coating material passes from the container to the nozzle, said nozzle having a narrow, elongated opening through which strip material to be coated may be drawn, a removable closure for a portion of said opening whereby providing two portions through which separate strips of material may be drawn independently, whereby, by the use of closures of different dimensions longitudinally of the opening, the apparatus 110 115 is adapted to apply coating to strips of different widths.

17. A coating apparatus comprising a nozzle member, means for securing the nozzle member to a container for coating material, means for maintaining said container and nozzle in inverted position whereby the coating material passes from the container to the nozzle, said nozzle having a narrow, elongated opening through which strip material to be coated may be drawn, a removable plate arranged to close a portion of said opening thereby providing two portions through which separate strips of material may be drawn independently, whereby, by the use of 120 125 130

plates of different lengths, the apparatus is adapted to apply coating to strips of different widths.

18. In a coating apparatus having a nozzle 5 for a container of coating material, and means for clamping the nozzle to the container, the combination of a plate hinged at one end to the nozzle and detachably latched at the other end to the nozzle in a relatively 10 fixed spaced relation thereto, thereby providing an elongated opening through which strip material to be coated can be drawn and forming, when the can and nozzle are in inverted coating position, a support for strip material to be coated, said plate, when the container and the nozzle are positioned with the nozzle-receiving end of the container upwardly, facilitating, by disengagement of the 15 latch and swinging of the plate about its hinge, the application of a new strip or strips of material to the nozzle.

19. A coating apparatus comprising an open-ended container for coating material, a closure nozzle for said container provided 20 with an elongated delivery opening, a removable closure dividing said opening into two parts thereby to adapt the apparatus for coating separate strips of material, a supporting plate hinged at one end to said nozzle arranged to hold said strips in close relation to 25 said delivery opening, control devices secured to said plate for controlling the thickness of the coating applied to the strip material, and means for securing the free end of the 30 plate to the nozzle, thereby to hold said control devices in predetermined relation to the delivery opening of the nozzle, facilitating by 35 disengagement of said securing means and the swinging of the plate about its hinge the 40 insertion of strips of material in the apparatus.

20. A dispensing apparatus comprising a normally stationary frame, an auxiliary U-shaped frame pivoted to said stationary 45 frame and constructed and arranged to receive an open-ended container between the sides of the frame and resting on the closed end thereof, a closure nozzle for the open end of said container, inclined toggles between 50 said closure nozzle and the open ends of the U-shaped frame constructed and arranged when pushed past dead center to rest against the side bars of the U-shaped frame and thereby to hold the container and nozzle in 55 the U-shaped frame.

21. A coating apparatus comprising a normally stationary frame, a swingable frame carried thereby and constructed and arranged to receive an open-ended container of coating material, a nozzle for the container, toggles for clamping the nozzle to the container and the nozzle and container to the swingable frame, a plate adjustably hinged at one end to the nozzle, and a latch holding 60 the other end of the plate to the nozzle, said 65

plate forming, when the can and nozzle are in inverted coating position, a support for a strip or strips of material drawn past the nozzle and, when the swingable frame, container and nozzle are positioned to hold the 70 can with its nozzle receiving end upwardly, arranged to facilitate, by disengagement of the latch and swinging of the plate about its hinge, the supplying of a new strip or strips of material to the nozzle. 75

22. In a coating apparatus comprising a normally stationary frame, a swingable frame trunnioned thereto and constructed and arranged to receive an open-ended container of coating material, a nozzle for the container, and means for clamping the nozzle to the container and the nozzle and container to the swingable frame, the combination of a plate hinged at one end and detachably latched at the other end to the nozzle and forming, when the can and nozzle are in inverted operative position, a support for a strip of material drawn past the nozzle and, when the swingable frame, the container and the nozzle are swung to position the container with its nozzle-receiving end upwardly, arranged to facilitate, by unlatching of the plate and swinging it about its hinge, the supplying of a new strip of material to the nozzle. 80

23. A dispensing apparatus comprising a frame constructed and arranged to receive a commercial container and a nozzle removable from the frame, one end of said nozzle being shaped to receive the open end of the container, guide members carried by the nozzle for sliding movement relatively to the frame to position the nozzle with respect to the frame, and means for clamping the nozzle to the container and the nozzle and container to the frame. 95

24. A dispensing apparatus comprising a frame constructed and arranged to receive a commercial container, a nozzle one end of which is shaped to receive the open end of the container, guide lugs carried by the nozzle for sliding movement relatively to the frame to position the nozzle with respect to the frame, and toggles for clamping the nozzle to the container and the nozzle and container to the frame. 100

25. A dispensing apparatus comprising a frame constructed and arranged to receive a commercial container, a nozzle one end of which is shaped to receive the open end of the container, a tubular gasket between the nozzle and the container arranged to make a tight joint between the nozzle and the container, guide members carried by the nozzle for sliding movement relatively to the frame to position the nozzle with respect to the frame, and means for clamping the nozzle to the container and the nozzle and container to the frame. 110

26. A coating apparatus comprising a nor- 115 120 125 130

mainly stationary frame, an auxiliary frame swingably mounted in said stationary frame and arranged to receive an open-ended container of coating material, a closure nozzle
5 for the open end of the container, a transverse member on one end of the swingable frame for engaging the closed end of the container, and clamping means at the opposite end of the swingable frame for holding the
10 nozzle, container and frame in assembled relation.

In testimony whereof I have signed my name to this specification.
